(57) **CLAIM**

The ornamental design for a video image display for monitor, as shown and described.

DESCRIPTION

FIG. 1 is a perspective view of a video image display for monitor;

FIG. 2 is a front view of the video image display for monitor of FIG. 1; and,

FIG. 3 is an enlarged view of the video image display for monitor of FIG. 1 shown without the broken line monitor for convenience of illustration.

The broken line showing of a monitor is included for the purpose of illustrating environmental structure and forms no part of the claimed design.

1 Claim, 3 Drawing Sheets**FIG. 1**

FIG. 2

FIG. 3
